DOMESTIC SANITARY APPLIANCE

Guillermo Zorraquin, Buenos Aires, Argentina

Application February 2, 1934, Serial No. 709,510
In Argentina February 8, 1933

4 Claims. (Cl. 4—7)

The present invention refers to sanitary appliances particularly for domestic use and has for its object the provision of a prophylactic water-closet bidet which by its special character, unique 5 in its class, and according to results obtained from models made for experimental purposes will render an important service as an element of prophylaxis and general hygiene, as by it, one of the most important sanitary problems which 10 has for a long time been under consideration, will be solved; for as is known, all water-closet bidets heretofore proposed have owing to being based on an oscillating type of apparatus or other 15 mechanical combinations designed for the release of the spray, proved to be very unpractical and complicated, and for this reason, have failed lamentably. Moreover, if it is taken into account that unless artificial pans are provided, the pan 20 corresponding to the bidet is the same as that of the water-closet, which is neither proper nor hygienic. Consequently a certain amount of independence is required, not in the manner that some manufacturers have adopted by employing oscillating pans, but by other characteristics that 25 make of the combination a practical and hygienic element like that which has been obtained by the present invention.

Therefore, the prophylactic water-closet bidet according to the present invention is arranged 30 in such wise that the pan is provided with two bodies which although not actually independent, are so in effect owing to the disposition of one with respect to the other, since it is a lengthened basin which, being so lengthened, has two sections, one 35 towards the front part, which corresponds to the bottom of the discharge, and another section which carries only the rose for the spray corresponding to the bidet, and in such wise that the opening in the seat corresponding to the water-closet, does not coincide with the above mentioned spray rose, so that this latter may not be affected 40 by the fecal matter when a person occupies the water-closet.

For the better understanding of this invention 45 and in what manner the same is to be performed a preferred embodiment will now be described reference being made to the accompanying drawing in which:

50 Fig. 1 is a vertical longitudinal section of the prophylactic water-closet bidet showing the disposition of the two sections of the pan, and the coincidence of the opening in the seat with only the part corresponding to the bottom of the pan, 55 when said seat is lowered.

Fig. 2 is a cross section along the line A—B of Fig. 1, of part of the water-closet bidet.

Fig. 3 is a plan of the closet illustrated in Fig. 1 with the seat raised to expose the entire pan.

In the various figures the like numbers and letters indicate like or corresponding parts.

As seen in the figures, *a* is the principal basin which, being lengthened (as best seen in Fig. 3) is divided into two sections 1 and 2 of which the first 1 corresponds to the fore part and has as a bottom the enclosure 3 communicating with the siphon 4 as a discharge. The separation wall 4' of said enclosure 3 determines the level of the liquid which forms the seal between the discharge pipe and the pan of the water-closet; this is, as 10 is known, in order to prevent the escape of bad odours by the volume of water retained when the pan has been flushed by means of the stream of water flowing into said pan from jets or flush pipes.

As in all water-closets, pipe 5 assists in the flushing, and communicates on the one hand with the surrounding pipe 6 which by means of the orifices 6' allows the water to issue by different points to flush the internal walls of the pan *a* 15 whilst on the other hand, from pipe 5 a drain 7 extends from pipe 5 and communicates with the lower part of enclosure 3 terminating in an opening directed towards siphon 4 so that the water that is expelled by a certain amount of pressure, 20 displaces towards the siphon all the fecal and liquid material that has collected in enclosure 3 and by so doing, this latter remains perfectly 25 clean with a content of pure water such as is clearly seen in Fig. 1.

The other section 2 that forms the back part of the pan *a* has a downwardly curved portion 8 the slope of which becomes progressively accentuated till it ends forwardly of the separating wall 4' and dips below liquid level, determined by the height 30 of said wall 4', thus serving as a separation 35 between the free surface of the water contained in the above named enclosure and in the bottom of siphon 4 (as shown in Fig. 1).

In the middle of the said portion 8 the rose 9 40 of the spray is fitted, said portion being intended to form the bidet section. The rose 9 is the end of passage 10 connected to the water supply pipe 11 having a corresponding tap 12, thus permitting 45 of the control of the volume of the spray. Said top 12 may be combined with another tap for hot and cold water, etc.

The whole of the water-closet bidet possesses a 50 seat 13 which has an opening 13' provided in its forward portion and so disposed with relation to 55

the forward end of the portion 8 that in the closed position of the seat a vertical surface drawn through the rearward portion of the inner edge of said opening will never cut the most forwardly 5 extending part of said portion 8. Thus said opening is concentric with section 1 of said basin *a* while the back of the basin otherwise section 2, corresponding to the bidet is covered and the covering extends forwardly so that when the water- 10 closet is used the fecal matter falls directly into enclosure 3 and cannot touch the forward end of the sloping portion 8 nor become deposited on the rose 8 of the bidet, so that this latter remains completely unaffected. The object is to ensure that 15 as a result of the disposition of both sections (1 and 2), the closet is essentially hygienic, so much so that immediately after the water-closet has been used and the corresponding flushing completed, the bidet may be used by raising seat 13 20 which on turning about hinges 14, exposes section 2 as is clearly shown in Figs. 1 and 3.

By this means the result is obtained that in the same basin *a* are found the necessary means for prophylaxis of all kinds of anal diseases and consequences constituting the combination within the maximum of hygiene and comfort, and so it is that the water-closet bidet referred to, lends itself specially for sanatoriums and hospitals, notwithstanding that they are equally apt for private 30 residences, especially in flats where bathrooms are built in the smallest possible space, etc.

It will be clear to those skilled in the art that in applying the invention in practice various modifications in the structure and design may be made 35 without thereby departing from the nature and scope of the present invention and all such modifications are held to lie within the scope of the appended claims.

Having now particularly described and specified the nature and scope of this invention, and in what manner the same is to be performed, what 40 I claim is:

1. An improved combined prophylactic water-closet and bidet comprising in combination a 45 hollow body, having a front wall, side walls, a rear wall and a bottom, said bottom having a perfora-

tion located therein nearer said rear wall and forming a portion of a siphon, an upwardly directed retaining wall extending along the forward lip of said perforation and merging at its ends into said sidewalls, a shelf like projection having a convex-like water-shedding upper surface and extending forwardly and downwardly from a line near the upper part of said rear wall its free end terminating below the liquid level determined by the height of said retaining wall and forwardly 10 of the latter, a channel provided in said projection terminating at the surface of said shelf in a spray rose located in the upper surface of the projection, said channel being connected at its other end to a controllable supply of water, and a 15 seat for the closet hinged to the upper end of the rear wall and having an opening so disposed that in its closed position a vertical plane drawn through the rearward portion of the inner edge of said opening will pass beyond the most forwardly 20 extending portion of the free extremity of said projection, so as to avoid deposition of fecal matter therein.

2. In an improved combined prophylactic water-closet and bidet, according to claim 1, a passage within said rear wall communicating at its upper end with a water supply pipe and with a channel provided within the upper edge of said body and having a plurality of discharge nozzles directed inwardly of the body, and at its lower 30 end with a conduit passing around the perforation in the bottom and terminating at a forward point of said bottom in a backwardly directed arm opening into the interior of the body.

3. An improved combined prophylactic water-closet and bidet according to claim 1 wherein the shelf like projection extends widthwise from one side wall to the other.

4. An improved combined prophylactic water-closet and bidet according to claim 1 wherein the shelf-like projection has a substantially plane downwardly inclined rear portion and an abruptly downwardly curved front portion.

GUILLERMO ZORRAQUIN.
